Patented Apr. 18, 1967

207,452

ICE BUCKET

Bennett H. Stayman, West Newton, Mass., assignor to Morgan & Company, Inc., Boston, Mass., a corporation of Massachusetts

Filed Feb. 2, 1966, Ser. No. 891

Term of patent 14 years

(Cl. D44—15)

FIG. 1 is a perspective view of an ice bucket showing my new design;

FIG. 2 is a front elevation view thereof; and

FIG. 3 is a top view thereof.

The essential features of my design are shown in full lines.

I claim:

The ornamental design for an ice bucket, as shown and described.
